US00D947776S

(12) **United States Design Patent** (10) **Patent No.:** **US D947,776 S**
Semboloni (45) **Date of Patent:** **** Apr. 5, 2022**

(54) **ELECTRICITY CHARGING STATION FOR ELECTRIC VEHICLES**

(71) Applicant: **ABB Schweiz AG**, Baden (CH)

(72) Inventor: **Alessandro Semboloni**, Laterina Pergine Valdarno (IT)

(73) Assignee: **ABB Schweiz AG**, Baden (CH)

(**) Term: **15 Years**

(21) Appl. No.: **35/509,092**

(22) Filed: **Jun. 11, 2019**

(80) **Hague Agreement Data**

Int. Filing Date: **Jun. 11, 2019**

Int. Reg. No.: **DM/206974**

Int. Reg. Date: **Jun. 11, 2019**

Int. Reg. Pub. Date: **Apr. 17, 2020**

(51) **LOC (13) Cl.** **13-02**

(52) **U.S. Cl.**

USPC **D13/108**

(58) **Field of Classification Search**

USPC D13/108, 110, 107; D14/307; D20/10

Primary Examiner — Rhea Shields

(74) *Attorney, Agent, or Firm* — Leydig, Voit & Mayer, Ltd.

(57) **CLAIM**

The ornamental design for an electricity charging station for electric vehicles, as shown and described.

DESCRIPTION

1. Electricity charging station for electric vehicles

1.1 : Bottom

1.2 : Front

1.3 : Top

1.4 : Left

1.5 : Back

1.6 : Perspective

1.7 : Right

In the reproductions, the broken lines are for the purpose of illustrating portions of the electricity charging station for electric vehicles and form no part of the claimed design.

1 Claim, 7 Drawing Sheets
